SOFT PLASTIC BAIT FOR FISHING

Joseph S. Wascow, 3048 N. Neva, Chicago, Ill. 60634

Filed Sept. 5, 1972, Ser. No. 286,050

Term of patent 14 years

Int. Cl. D22—05

U.S. Cl. D22—27

FIG. 1 is a plan view of a soft plastic bait for fishing embodying the invention.

FIG. 2 is a longitudinal side elevational view of the bait of FIG. 1.

FIG. 3 is a longitudinal bottom view showing the underside of the bait of FIG. 2.

FIG. 4 depicts the front end of the bait as shown in FIG. 2.

FIG. 5 is a fragmentary perspective view taken with reference to the line 5—5 of FIG. 2 and showing the middle rear portion of the bait as viewed from above.

FIG. 6 is a fragmentary perspective view taken with reference to the line 6—6 of FIG. 2 and showing the middle rear portion of the bait as viewed from below.

FIG. 7 is a transverse sectional view taken with reference to the line 7—7 of FIG. 2.

FIG. 8 is a transverse sectional view taken with reference to the line 8—8 of FIG. 2; and

FIG. 9 is a transverse sectional view taken with reference to the line 9—9 of FIG. 2.

I claim:

The ornamental design for a soft plastic bait for fishing, as shown.
